ATTORNEY

UNITED STATES PATENT OFFICE

ANDREW B. ALLDREDGE, OF SWEETWATER, TEXAS

COOLING AND VENTILATING APPARATUS

Application filed May 31, 1930. Serial No. 458,795.

This invention relates to a cooling and ventilating apparatus designed for use in private residences, apartment houses, hotels, and in fact any building where it is desired to maintain a comparatively cool temperature and to purify the air, and the invention has as its primary object to provide a cooling and ventilating apparatus, for the purpose stated, embodying means whereby air, supplied to the apparatus under pressure will be cooled and purified by the presence of water in minute particles, within the apparatus.

Another object of the invention is to provide an apparatus of this class which will be simple in construction and inexpensive to install and which may be maintained in operation with a minimum consumption of electric current.

Another object of the invention is to provide an apparatus of the class referred to above in which water, delivered in a spray at the top of the apparatus, will be separated into fine drops and film over foraminous baffles, arranged within the casing of the apparatus, so that sufficient moisture will be supplied to the air, and in an imperceptible amount so as not to cause discomfort.

Another object of the invention is to provide for the circulation of water in a finely divided form in the casing of the apparatus in the path of travel of the air currents, and the means for effecting circulation of the water being of such nature that a constant supply of water to the apparatus will not be required.

In the accompanying drawing the view illustrating the invention is a vertical sectional view, parts being shown in elevation, and illustrating the apparatus.

The apparatus comprises a hollow cylindrical casing 1 which is closed at its lower end by a bottom 2 mounted upon a suitable base 3 and this casing may be of any suitable metal and is provided, near its bottom, with an air intake spout 4 within which is mounted a shaft 5 having mounted upon it a fan 6. The shaft is also mounted in a bearing 7 at the opposite side of the casing and is connected with the shaft of an electric motor 8. The casing is open at its top and a spider 9 is

mounted in said open top and supports a flared nozzle 10 to which is connected the delivery end of a water supply pipe 11 which leads from a centrifugal pump 12 mounted upon the base 3, the intake pipe of the pump indicated by the numeral 13, being placed in communication with the interior of the casing 1 near the bottom thereof, by a suitable coupling nipple 14 upon the wall of the casing.

Pulleys 15 and 16 are mounted upon the shaft 5 and the pump shaft, and the endless belt 17 is trained about the pulleys. At this point it will be evident that, when the motor 8 is in operation, rotary motion will be imparted to the fan shaft 5 so as to create a current of air flowing through the spout 4 and into the casing and out through the open top thereof and, at the same time, the pump 12 being operated by a motor 8, water which is maintained at a proper level within the casing, will be pumped by the pump 12, through the pipe 11 and delivered through the nozzle 10 at the top of the casing.

The means for supplying water to the casing comprises a water supply pipe 18 having a cut-off valve 19 interposed therein so that the supply of water may be all together cut off or suitably regulated as desired and this pipe leads into the casing near the bottom thereof, and a regulating valve 20 is interposed within the pipe, within the casing, a stem 21 being connected with the stem of the valve 20 and a float 22 being mounted at the inner end of the stem so that, when the level of the water in the casing falls below the predetermined level, the lowering of the float will effect opening of the valve 20 to provide for the supply of a further volume of water until the required level is reached.

In order that the water, delivered through the spout 10, may be broken up and distributed in fine particles throughout the height of the casing, a plurality of foraminous baffles are arranged in a vertical series, at intervals in the height of the casing and one of these baffles, indicated by the numeral 23, is of conical form and of wire netting of relatively large mesh and other baffles 24 and 25 which are of wire netting are also arranged within the casing and above one another in

the order mentioned and below the corresponding baffle 23 and the baffles 24 and 25 are of a finer mesh than the respective baffle 23.

- 5 As a consequence, water which is delivered from the spout 10 will be sprayed onto the uppermost one of the baffles 23 and, falling through the openings in the baffle, will reach and spread over the baffle 24 and pass through 10 the openings in this baffle and be spread over the baffle 25, and at this point it will be evident that due to the manner in which the water, introduced at the top of the casing is subjected to the air currents flowing upwardly 15 through the casing and the water is divided into fine drops, there will be sufficient moisture in the air delivered from the casing, to satisfy all requirements and yet not in such volume as to cause inconvenience or 20 discomfort. One of the baffles 23 is arranged immediately below the nozzle 10 and open top of the casing, and the lowermost of the baffles 23 is arranged immediately above the upper side of the spout 4 through which air 25 is introduced into the casing and, in order that water may be prevented from entering the spout 4, a baffle flange 26 is provided about the top and sides of the opening in which the delivery end of the spout is arranged.
- 30 In order that the water delivered into the casing and passing through the baffles 23, 24 and 25 may be further mutually commuted, a baffle 27 of fine mesh netting is arranged within the casing and this baffle is of the concave 35 form shown in the drawing and extends from that side of the casing in which the spout 4 is mounted and close to the lower side of the delivery end of the spout and the baffle is inclined upwardly from this side to the 40 opposite side of the casing so that the blast of air, which is delivered into the casing by the fan 6, will be influenced to travel in an upward direction, thus avoiding any disturbance of the water in the lower end of the casing and further commuting the water which 45 has been deposited on the said surface of the baffle 27.

What I claim is:—

1. A cooling and ventilating apparatus 50 comprising a casing, open at its top, an air intake spout extending laterally from the lower portion of the casing, a fan in said spout for delivering air into the casing, a water supply pipe communicating with the casing below the spout, means for conducting water from the casing and delivering the same into the casing at the top thereof, a foraminous baffle within the casing in the path of the delivered water, and a second 55 foraminous baffle within the casing curving upwardly from that side of the casing at which the spout is located, and at a point below the spout, and extending to the opposite side of the casing.
- 60 2. A cooling and ventilating apparatus 65

comprising a casing, open at its top, an air intake spout extending laterally from the lower portion of the casing, a fan in said spout for delivering air into the casing, a water supply pipe communicating with the casing below the spout, means for conducting water from the casing and delivering the same into the casing at the top thereof, a foraminous baffle in the casing in the path of the delivered water, and a flat foraminous baffle and of a mesh finer than that of the first mentioned baffle.

3. A cooling and ventilating apparatus comprising a casing, open at its top, an air intake spout extending laterally from the lower portion of the casing, a fan in said spout for delivering air into the casing, a water supply pipe communicating with the casing below the spout, a float valve in said pipe for controlling the supply of water therefrom, means for conducting water from the casing and delivering the same into the casing at the top thereof, and a foraminous baffle within the casing in the path of the delivered water, the said water conducting 85 means comprising a pipe having its delivery end presented at the top of the casing, a rotary pump to which the intake end of the pipe is connected, the intake of the pump being in communication with the intake of the casing at the bottom thereof, and a nozzle at the delivery end of said pipe.
